UNITED STATES PATENT OFFICE.

CHARLES E. PENDLETON, OF ENID, OKLAHOMA.

DOUBLE-ACTING POWER-WRENCH.

1,353,417.

Specification of Letters Patent. Patented Sept. 21, 1920.

Application filed November 22, 1919. Serial No. 339,888.

To all whom it may concern:

Be it known that I, CHARLES E. PENDLETON, a citizen of the United States, residing at Enid, in the county of Garfield and State 5 of Oklahoma, have invented certain new and useful Improvements in Double-Acting Power-Wrenches, of which the following is a specification, reference being had to the accompanying drawings.

10 This invention relates to an improved double acting power wrench, particularly adapted for taking off and putting on nuts and the like, and one of the objects of the invention is to provide a very simple, efficient and practical device of this kind, in which there is involved novel features of construction.

Another object of the invention is to provide a double acting wrench including a 20 driven wrench member either end of which being adapted to unscrew and screw on a nut, or one end adapted to unscrew a nut while the other end is adapted to screw on a nut and vice versa, in combination with 25 means for driving the wrench member and means carried by the casing of the wrench member for controlling said operating means.

A further object of the invention is to 30 provide a wrench mechanism including a flexible connection with a source of power remote from the wrench mechanism, and means in close position to the casing of the wrench mechanism and having a housed 35 flexible connection to a clutching means adjacent the source of power, for controlling the same, whereby the wrench mechanism may be operated in and out of gear with the source of power.

40 A still further object of the invention is to provide a double acting wrench mechanism including a wrench member and means carried thereby so geared to a driving element that when the driving element is at 45 rest, said means on the wrench member will act as a lock in connection with the driving element, so that by manipulating the casing of the wrench mechanism, the wrench member may be used for loosening nuts which

50 have become stuck or thread bound before applying the power to unscrew the nut. This locking connection between the wrench member and the driving element when the driving element is at rest also enables the 55 operator to manipulate the housing of the wrench mechanism, to impart a final turn

manually to the nut in order to thoroughly tighten the same.

An additional object of the invention is to provide a flexible shaft connection between the source of power and the wrench mechanism so that when the source of power is operated in one direction or the other by a clutch (not shown) the flexible shaft may be operated in either direction. 65

Further, it is the aim to provide housing means for the flexible shaft connection between the source of power and the wrench mechanism, and also a flexible housing means for the pull cord connection between 70 an operating lever and the clutch mechanism, for moving the clutch in and out of gear.

The invention also aims to provide a wrench mechanism having driving gear connections direct with a source of power in combination with means carried by the casing or motor or source of power, for operating a driving element of the source of power in and out of gear with a driven member of 80 the wrench mechanism. 75

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed. 85 90

The invention comprises further features and combination of parts, as will be hereinafter set forth, shown in the drawings and claimed.

In the drawings:—

Figure 1 is a view showing the improved wrench mechanism in elevation, and illustrating the flexible shaft connection with a pulley, which is driven by a source of power such as a motor, through the medium of a 100 belt connection.

Fig. 2 is a sectional view through the wrench mechanism and the flexible shaft and showing the pulley, which is driven by the source of power. 105

Fig. 3 is a sectional view through the wrench mechanism at right angles to the showing in Fig. 2.

Fig. 4 is a sectional view on line 4—4 of Fig. 3.

Fig. 5 is an enlarged detail sectional view 110 of a portion of the flexible shaft, particu-

larly at the point where it is connected to the driving pulley.

Fig. 6 is a sectional view showing the wrench mechanism as applied direct to the source of power, which is adapted to be carried in the hand of the operator and means carried by the hand hold adapted for operating the clutch to operate the source of power, such as a motor, in and out of gear with the wrench mechanism.

Referring more especially to the drawings 1 designates a conventional form of electrical motor, though not necessarily, for it is obvious that any other suitable power means may be employed for operating the mechanism, and 2 denotes a shaft which is mounted in suitable bearings in close position to the motor, and loosely mounted upon the shaft is a pulley 3. This pulley is operatively connected to a pulley 4 of the motor shaft by means of the belt 5. One face 6 of the pulley 3 constitutes a friction clutch and keyed by means of a feather 7 to the shaft 2 is the hub 8 of a movable friction clutch 9. A coil spring 10 is interposed between the loosed pulley 3 and the movable clutch member in order to hold the movable clutch member normally out of gear with the friction clutch pulley. The larger end 11 of the shaft 2 is mounted in a tubular casing 12, which constitutes a bearing for the larger end 11 of said shaft. A sleeve 13 is connected by means of threads or the like 14^a to the casing or bearing 12. The larger end 11 of the shaft 2 has a reduced extension 14.

A wrench mechanism is provided and is adapted to be operated by means of the pulley 3, when the movable clutch member is moved into engagement with the friction clutch face 6 of said pulley. The wrench mechanism comprises a hollow disk shaped housing 15, which houses a worm gear 16. The housing 15 comprises two parts, which are fastened together as shown at 17. The object of constructing the housing 15 in two parts is to permit the worm gear to be placed in the housing. Projecting from opposite sides of and forming integral connections with the two parts of the housing 13 are axially aligned tubular extensions 18 and 19 in bearings 20 of which a driven wrench member or shaft 21 is mounted. The worm gear 16 is mounted on and carried by the wrench shaft 21. The opposite ends of the wrench shaft 21 terminate in extensions 22 preferably square in cross section, though not necessarily. These extensions 22 are designed to fit correspondingly shaped openings 23 of suitable socket wrenches 24. The socket wrenches 24 have hexagonal nut engaging openings 25, so that when the wrench shaft 21 is rotated in one direction or the other, the socket wrenches will act to remove and apply nuts or the like.

The housing or casing 19 is provided with a tubular housing 26, which extends tangentially with relation to the disk shaped housing. Mounted in bearings 27 of the tubular housing 26 is a driving shaft 28, which is provided with a worm 29 meshing with the worm gear 16.

A flexible shaft 30 connects the extension 14 and the driving shaft 28. A portion of the flexible shaft comprises a plurality of sections 31 connected as at 32. One of the sections 31 is connected at 33 to the driving shaft 28, so that the movement may be imparted to the shaft 28. Another portion of the flexible shaft comprises a plurality of sections 34, which are connected as at 35. One of the sections 34 is connected as at 36 to the extension 14 of the end 11 of the shaft 2, while a certain other section 34 is connected at 37 to one of the sections 31. It will be noted that the sections 34 are smaller than the sections 31, so that the portion of the flexible shaft which includes the smaller sections may more easily flex than the portion of the shaft which includes the sections 31. The various sections 31 and 34 which are connected at 32, 33, 35 and 37 have their connections so arranged with respect to each other as to permit the various sections to flex and universally move in different directions, all the while the shaft is capable of rotating. A housing 38 preferably made up from a coil of springs incloses the smaller sections 34 of the flexible shaft, thereby constituting a bearing for the smaller sections of the flexible shaft and at the same time holding them rotatively in alinement. One end of the coil spring housing 38 is secured by a suitable pin 39 to one end of one of the sections 31, while the other end of the coil spring housing is connected to the extension 14 of the end 11 of the shaft 2 by the pin 40. A second flexible housing 41 preferably constructed from a coil spring incloses the housing 38. This housing 41 is constructed from a larger coil spring than the coil spring forming the housing 38. This housing 41 forms a bearing for the housing 38, in which a flexible portion of the housing 38 rotates. It will be noted that the flexible housing 41 incloses the larger section of the flexible shaft, and constitutes a bearing therefor and also means to hold the section 31 operatively in alinement. The larger flexible spring housing is connected in any suitable manner as at 42 to the end of the tubular housing 26.

A lever 43 is pivoted at 44 to the bearing casing 12 and is provided with forks 45 which straddle the larger portion 11 of the shaft 2, and engage the edge of the hub 8 of the movable friction clutch so that when the lever is tilted in the direction of the arrow *a*, the friction clutch member 9 will be moved to frictionally engage the clutch face 130

of the pulley 3, thereby driving the shaft 2, which in turn operates the flexible shaft and also the shaft 28. The rotating of the shaft 28 also operates the worm 29 which imparts movement to the worm gear 16. It is obvious that by operating the motor in either direction, the wrench shaft 21 may be operated in either direction so as to remove and apply nuts through the medium of the 5 socket wrenches which may be carried by the ends of the wrench shaft 21. A pull cord or shaft 46 is connected to the lever 43 and passes through an opening 47 in the wall of the sleeve 13. This pull cord or 10 shaft 46 is housed by means of a coil spring housing 48, which lies against the larger coil spring housing 41. The coil spring housing 48 constitutes means to hold the pull cord in alignment and to permit it to 15 easily operate, so as to tilt the lever 43. When the lever 43 is tilted the movable friction clutch member 9 is actuated against the action of the coil spring 10. The coil spring housing 48 of the pull cord, at one end, is 20 arranged in a recess 50 of the inner part of the wall of the sleeve 13 which is provided with a shoulder 51. The other end of the coil spring housing 48 of the pull cord or shaft 46 is mounted in a recess of the outer 25 portion of the wall of the housing or casing 26 at one of its ends. The pull cord or shaft at one end extends through an opening 52 at one end of the casing 26 and is connected to an arm 53 of a lever 54, which is pivoted 30 to 55 to the casing 26. The end portion of the casing 26 has a shoulder 56. In surrounding relation to the larger spring coil housing 41 is a tubular covering 57, which may be constructed of any suitable pliable 35 or flexible material, such as canvas or leather, or a composition of either so as to not only keep the dust from the spring housing, but also to act as a protection for the various parts of the flexible shaft, and to 40 hold them in operative relation, and furthermore to permit the shaft to be easily handled by the operator. One end of the tubular covering is fitted over the shoulder 56 of the end of the casing 26 and is bound 45 to the casing by means of a suitable wrapping of wire or the like as indicated at 58. The other end of the tubular covering is 50 fitted over the shoulder 51 and is likewise secured to the sleeve 13 by means of a wrapping of wire or the like as indicated at 59. It is to be noted that when the lever 54 is 55 rocked in the direction of the arrow *b* a pull action is imparted on the pull cord or shaft 46 thereby oscillating the lever 43 which 60 will move the clutch in engagement with the friction clutch surface of the pulley thereby transmitting motion to the flexible shaft. It will be observed that the source of power is easily manipulated by the operator, who 65 may hold the casing or housing 26 and posi-

tion it for the purpose of applying and removing nuts and the like. It is obvious that by means of the wrench shaft or element, one nut may be screwed on and another nut removed and vice versa, it depending entirely upon the direction of rotation of the wrench shaft or element 21. 70

In Fig. 6, it will be noted that the wrench mechanism housing or casing forms an integral part as at 60 with the casing 61 of a 75 motor 61^a, preferably of the electrical type and which carries a hand hold or handle 62 so that the motor of the wrench mechanism can be moved from one place to another, it depending upon the length of the electrical 80 connections between the motor and the source of current supply. In this type of device, the motor 61^a has its shaft 61^b movable axially. In other words, the shaft 61^b is designed to have, in any suitable manner, 85 a sliding connection with its armature (not shown) or the shaft of the armature may move axially together. This movement is very slight, and in so far as the invention is concerned, it is immaterial to illustrate the 90 construction of the motor and the armature, whereby the shaft is capable of such longitudinal movement. However, it is the aim to have the shaft 61^b mounted so that it is capable of longitudinal movement axially 95 through the motor, so that a friction clutch member 63 on one end of the shaft 61^b may contact with the friction clutch member 64 which is carried by the shaft 65 so that when the motor shaft 61^b is moved longitudinally, the two friction clutch members 100 will contact frictionally and cause revolute movement to the shaft 65. In this way, by means of the worm 66, power is transmitted to the worm gear 16 and which in 105 turn operates the wrench shaft 21 as in the construction hereinbefore described. Owing to the clutch members 63 and 64 being in frictional contact with each other, they eventually become considerably worn, and 110 in order to take up for this wear, a set screw *h* is threaded through a portion of the casing 60 so as to contact with the end of the shaft 65. For instance, by rotating the thumb screw *h* after backing the lock nut 115 *m*, the shaft 65 may be moved longitudinally, so as to position the clutch 64 closer to the clutch member 63 so that but a very slight movement of the motor shaft 61^b is necessary, to cause a transmission of power 120 from the motor shaft 61^b to the shaft 65. After the thumb screw *h* has been set, the lock nut *m* may be tightened up to hold the thumb screw in place. The thumb screw 125 may be adjusted to move the shaft 65 longitudinally so as to position the friction clutch member 64, so that but a very infinitesimal space may be permitted to remain between the two friction clutch members. Pivottally mounted at 71 on a part of the hand grip is 130

a shaft actuator 72. One end 73 of this actuator contacts with the conical end of the motor shaft 61^b so that when the actuator 72 is rocked upon its pivot, the motor shaft 61^b may be moved longitudinally. The other end of the actuator 72 terminates in an extension 74 which may be gripped by the fingers of the hand of the operator to oscillate the actuator 72. The operation of the actuator and the movement of the motor shaft 61^b should be apparent from the disclosure in the drawing in connection with the above description. The hand grip has a housing 68 forming a part thereof, and projecting from this housing is a lever 70. A suitable mechanism (not shown) is designed to be mounted in the housing 68 for electrical connections (not shown) with the motor. It is the design, that by the manipulation of the lever 70, the mechanism in the housing 68 may be operated so that through the medium of the electrical connections (not shown) with the motor, the motor may be stopped and started. The hand hold 62 is provided with projecting lugs 67 to prevent the hand of the operator from slipping.

The invention having been set forth, what is claimed as new and useful is:—

30 1. In a wrench mechanism including a wrench element, the combination with a casing for said element, a source of operating means remote from the wrench element including a clutch mechanism, a flexible connection between the operating means and the wrench element and being operatively controlled by the clutch mechanism, and means carried by the casing and having operative connection with the clutch mechanism for moving an element of said clutch mechanism into and out of engagement with the operating means.

45 2. In a wrench mechanism including a wrench element, the combination with a casing for said element, a source of operating means remote from the wrench element including a clutch mechanism, a flexible connection between the operating means and the wrench element and being operatively controlled by the clutch mechanism, means housedly mounted in and conforming to said flexible connection and being operatively connected to the clutch mechanism for manipulating the same, and means carried by the casing of the wrench element for operating said last mentioned means.

50 3. In a wrench mechanism including a wrench element, the combination with a casing for said element, a source of operating means remote from the wrench element including a clutch mechanism, a flexible connection between the operating means and the wrench element and being operatively controlled by the clutch mechanism, a flexible pull member conforming to and being

70 housedly mounted in the flexible connection and being operatively connected with the clutch mechanism for controlling the same for moving a clutch member of the clutch mechanism into and out of engagement with the operating means and a lever pivotally mounted on the casing and the wrench element for imparting pulling actions upon the pull member.

75 4. In a wrench mechanism including a wrench element, the combination with a casing for the wrench element, of an operating mechanism remote from the element and including a clutch mechanism, a flexible shaft operatively connected to the operating means and being controlled by the clutch mechanism and having connections with the wrench element, a flexible pull cord connected to the clutch mechanism and conforming to the flexible shaft, and a lever 80 mounted upon said casing and connected to the pull cord for manipulating a member of the clutch mechanism in and out of engagement with the operating means for operatively controlling the flexible shaft.

85 5. In a wrench mechanism including a wrench element, the combination with a casing for the wrench element, of an operating mechanism remote from the element and including a clutch mechanism, a flexible 90 shaft operatively connected to the operating means and being controlled by the clutch mechanism and having connections with the wrench element, a flexible pull cord connected to the clutch mechanism and conforming to the flexible shaft, and a lever mounted upon said casing and connected to the pull cord for manipulating a member of the clutch mechanism in and out of engagement with the operating means for operatively controlling the flexible shaft, a flexible 95 housing for the flexible shaft, a flexible housing for the pull cord carried by the housing of the flexible shaft, and a flexible covering for the two housings.

100 6. In a wrench mechanism including a wrench element, the combination with a casing for the wrench element, of an operating mechanism remote from the element and including a clutch mechanism, a flexible shaft 105 operatively connected to the operating means and being controlled by the clutch mechanism and having connections with the wrench element, a flexible pull cord connected to the clutch mechanism and conforming to the flexible shaft, and a lever mounted upon said casing and connected to the pull cord for manipulating a member of the clutch mechanism in and out of engagement with the operating means for operatively controlling the flexible shaft, said flexible shaft comprising two parts of relatively different proportions, each part comprising universally connected sections, a flexible spring housing covering one of the 110 115 120 125 130

parts, a larger spring housing covering the first spring housing and the other part of said shaft, a spring housing for the pull cord, and a tubular flexible covering for the 5 several housings.

7. In a wrench mechanism including a wrench element, adapted to carry wrench devices at both ends, the combination with a casing, a manually gripped means connected to the casing for supporting the same and holding the wrench element to its work, a worm gear on the wrench element and being housed in said casing, a driven member operatively connected to the worm gear, 10 an operating means having clutch controlled operative connections with the driven member, and means carried by the manually gripped means for manually controlling said connections.

8. In a wrench mechanism including a 20 wrench element, the combination with a casing for said element, a source of operating means remote from the wrench element including a clutch mechanism, a connection between the operating means and the wrench 25 element and being operatively controlled by the clutch mechanism, means adjacent said connection and adapted to be manually gripped for holding the wrench element to its work, and means carried by the manually gripped means and operatively connected to the clutch mechanism for manipulating the same to control the operation of the wrench mechanism. 30

In testimony whereof I hereunto affix my 35 signature.

CHARLES E. PENDLETON.
